Maurice L. Caton, Inventor

By his Attorney, Chas. W. Martinez

Patented Feb. 21, 1928.

UNITED STATES PATENT OFFICE.

MAURICE L. CATON, OF QUEBEC, CANADA, ASSIGNOR TO THE BARRETT COMPANY,
A CORPORATION OF NEW JERSEY.

ROOFING STRIP.

Application filed January 25, 1923. Serial No. 614,784.

This invention relates to a process of forming roofing materials and the product thereof. It relates more particularly to the type of roofing material which is formed 5 from a base of fibrous or felted material that is saturated with water-proofing material and then coated with plastic material which has wear-resisting material such as mineral matter applied to the outside 10 surface thereof.

The invention will be understood from the description in connection with the accompanying drawings in which

Fig. 1 is a plan view of the roofing sheet;

Fig. 2 is an edge view of same; and

Fig. 3 represents in part mechanism showing how the article can be made.

In the drawings, reference character 1 designates a base of fibrous material which 20 may be made from paper making stock or other fibrous material and may then be saturated with liquid waterproofing material such, for example, as tar, by passing the same through a bath of the waterproofing material as is common and well known in 25 this art. The waterproofed sheet 1 may then have applied to one side thereof a layer 2 of plastic material such as pitch or asphalt, for example, which may be applied in the hot 30 or liquid state in the usual or well known manner and then be allowed to cool and harden. This layer 2 will preferably be applied along one edge of the sheet 1 thereby leaving a wide uncoated margin 3.

After the coating 2 has been applied, certain sections or areas of the same may be covered with or have applied thereto a coating 4 of plastic bituminous material such as asphalt, for example. In Fig. 3 is illustrated somewhat diagrammatically a device 35 by which the spots or portions of the coating 2 may have the plastic material 4 applied thereto in segregated areas. In this figure reference character 6 designates a tank in

45 which the plastic material 7 may be kept in a plastic or semi-liquid condition by being kept hot in any convenient manner. A drum 8 having segments or sections 9 separated from each other by longitudinal grooves 10 50 dips into the plastic material 7 and revolving against the coating 2 of the sheet 1 as it passes thereover in the direction of the arrow, the plastic material is applied to the coating 2 in the areas designated by reference character 4. The sheet then passes

around the roller 11 and under a receptacle 12 from which granular particles 13 of wear-resisting material such as crushed stone, slate, etc., are sprinkled thereon. As the areas 4 of plastic material are still warm 60 and sticky, the particles 13 will cling thereto, but the particles which fall outside of these areas upon the cool, hard coating 2 will not stick thereto but will fall off when the sheet is turned. As the sheet passes from 65 under the container 12 it may be caused to pass between pressure rolls 14, 15 which will serve to press the granular particles 13 more firmly into the plastic material 4. The plastic material will preferably be applied 70 in shapes indicated in Fig. 1 and in such a manner that an uncoated marginal edge 16 and the strips 17 of the coating 2 will be left exposed.

In applying the strip of roofing material 75 to a roof deck, it may be laid either horizontally or vertically or at an acute angle to the edge of the roof. After the first sheet 1 has been laid along the roof, cementitious material such as hot tar or soft asphalt, for 80 example, may be applied upon the uncoated portions 3 and then a second strip laid thereover with its lower edge in contact with the exposed edge 16 of the coating layer 2 and so on until the entire roof is covered. The 85 exposed strips 17 of superposed layers may be made to lie in the same line with each other or they can be staggered.

The spots or areas 4 may be applied in shapes other than rectangular and the color 90 of the mineral particles 13 should in all cases be such as to contrast with the color of the coating 2. By the use of these strips an attractive looking roof can be made having the 95 lines 16 and 17 of contrasting color with the mineral matter 13 so as to make patterns of the desired sort.

I claim:

1. A strip of roofing material having a layer of plastic waterproofing material on 100 one side thereof free from mineral surfacing material, portions of said plastic waterproofing material being thickened by a second layer of plastic waterproofing material homogeneously united with the first 105 layer, the thickened portions having wear-resisting material applied thereto.

2. A strip of roofing material having a layer of plastic material on one side thereof 110 free from mineral surfacing material, por-

tions of said plastic material being covered with a layer of plastic material homogeneously united with the first layer, said portions having a coating of wear-resisting material applied thereto.

3. A roofing strip consisting of a fibrous base saturated with waterproofing material, a layer of plastic waterproofing material on one side thereof free from mineral surfacing material, portions of said layer of like areas being uniformly thickened by a second layer of plastic waterproofing material homogeneously united with the first layer and wear-resisting material partially embedded in the surface of the thickened portions.

4. A roofing strip consisting of a fibrous base saturated with waterproofing material, a layer of plastic waterproofing material approximately one half the width of the strips, applied to one side and at one edge thereof and free from mineral surfacing material, portions of said layer of like areas being uniformly thickened by a second layer of plastic waterproofing material homogeneously united with the first layer and wear-resisting material partially embedded in the surface of the thickened portions.

5. A roofing strip consisting of a fibrous base saturated with waterproofing material, a layer of plastic waterproofing material, approximately one half the width of the strips, applied to one side and at one edge thereof and free from mineral surfacing material, parallel portions of said layer of like areas being uniformly thickened by a second layer of plastic waterproofing material homogeneously united with the first layer and wear-resisting material partially embedded in the surface of the thickened

portions, the outer edge of the thickened portions being substantially flush with the edge of the strips and the inner edge of the thickened portions terminating short of the inner edge of the first named layer.

6. A roofing strip consisting of a fibrous base saturated with waterproofing material, a layer of plastic waterproofing material, approximately one half the width of the strips, applied to one side and at one edge thereof and free from mineral surfacing material, parallel rectangular portions of said layer of like areas and of a length less than the width of said layer being uniformly thickened by a second layer of plastic waterproofing material homogeneously united with the first layer and wear-resisting material partially embedded in the surface of the thickened portions.

7. The process which comprises applying plastic material to one side of a roofing sheet, thickening portions of said plastic material by applying thereto and homogeneously uniting therewith a second layer of plastic material and applying wear-resisting material to said second layer while it is still in a plastic state.

8. The process which comprises applying plastic waterproofing material to approximately one half of one side of a roofing strip at one edge thereof, thickening parallel rectangular portions of said plastic waterproofing material by applying thereto and homogeneously uniting therewith a second layer of plastic material and applying wear-resisting material to said second layer while it is still in a plastic state.

In testimony whereof I affix my signature.

MAURICE L. CATON.
